UNITED STATES PATENT OFFICE.

WALTER OPEL, OF LEIPZIG, GERMANY, ASSIGNOR TO THE FIRM GEORGI & CO., OF LEIPZIG, GERMANY.

PICTURE FRAME.

Application filed April 27, 1923. Serial No. 634,997.

To all whom it may concern:

Be it known that I, WALTER OPEL, a citizen of the German Republic, residing at Leipzig, Germany, have invented certain new and useful Improvements in Picture Frames (for which I have filed an application for patent in Germany on the 27th of January, 1921), of which the following is a specification.

10 My invention relates to picture frames or the like and it has particular relation to frames which are made of paper strips, for instance such paper strips as are at present the waste material from telegrams.

15 Picture frames are now made from paper strips which are wound upon themselves and solidly glued together by pressure, and after being dried the material can be worked in exactly the same manner as wood.

20 Frames of this type in which the several layers of paper remain superposed in the position in which they are wound up are hard like wood upon the surface but they warp easily and do not possess sufficient resistance against bending stress.

25 My invention, however, permits the manufacture of serviceable, permanent picture frames, because the superposed layers or strips of the frame body, which latter is produced in a well known manner by winding up paper strips and uniting the same with glue, are displaced in a transverse direction by pressing tools in such a manner that a frame in any desired profile is produced.

30 Since the front of the frame is pressed outwardly, the back of the same is hollow whereby not only is the solidity of the frame increased but the warping of the same during drying of the adhesive between the strips is prevented.

35 My invention may be best understood by reference to the following description in connection with the accompanying drawing, wherein:

40 Figure 1 is an elevational, sectional view of a wound body in the first stage of manufacture, said body being adapted for use in the production of a picture frame;

45 Fig. 2 is an elevational, sectional view of said body after the frame has been profiled by the use of suitable tools; and

50 Fig. 3 is a perspective view of a picture frame formed in accordance with my invention.

55 In forming a frame in accordance with

my invention a body, consisting of layers "a" of paper strips with an intermediate layer "b" of glue, is formed by winding up the strips in the manner shown in Fig. 3.

For purposes of clarification of the drawing, comparatively few of the paper layers only are shown, and these latter thick, but in reality a great number of thin layers may be used.

After the body is wound up, as shown in Fig. 1, pressure is applied to the upper surface of the frame, and any desired layers are displaced (as shown in Fig. 2) to form any desired profile on the frame. While such displacement may be employed in any desired way, the preferred method is to use a pressing tool which has the same contour as is desired shall exist on the front of the picture frame.

As raw material for picture frames formed in accordance with my invention, waste telegram strips are preferably used, since these are not only quite cheap, but contribute the further advantage that they are gummed on the back so that in winding them up they may be drawn over a wetting device—no gumming cylinder being required, whereby any disagreeable smearing of the adhesive is prevented.

In some cases strips of different widths can be used successfully to form the original body, whereafter the layers are shaped as heretofore described in order to produce a profile of different heights and depths. The now vertically directed edges of the strips, which are thus produced in connection with my frame, oppose, when dried, owing to their hardness, considerable resistance to the fashioning, for instance, of the grooves or ledges designed to receive the picture, or the production of ornamental beads.

Furthermore, any difficulty met in this direction can be overcome by making the groove or ledge to receive the picture of a separate strip of cardboard, which is fixed to the coiled paper strip. This is best shown in Figs. 2 and 3, in which A is the ledge made of a paper strip, B is the picture and d is a bead serving as an ornament.

Having thus described my invention, what I now claim as new and desire to secure by Letters Patent of the United States is:

1. A picture frame or the like having the sides thereof formed of continuous successive layers of material, said layers being

displaced, to a predetermined extent, to provide a desired profile or design on the front edge of said frame, the rear edge of said frame being of irregular contour because of said displacement.

2. The process of making a picture frame or the like which comprises winding a strip of material continuously upon itself to form a desired contour and thereafter displacing certain of the turns in a direction perpendicular of the area of the frame to provide a profile on said frame.

3. The process of making a picture frame or the like which comprises winding a strip of material continuously upon itself to form a desired contour, adhesive material being positioned between the turns of said material to bind the material into a compact mass, and thereafter displacing certain of the turns in a direction perpendicular of the area of the frame to provide a profile on said frame.

4. An improved picture frame made of strips of paper wound up in shape in which the wound up layers of paper strips are displaced in transverse direction in order to produce a profiled body, to increase the resisting capability of the body and to prevent the warping of the frame, the front and rear edges of said frame being complementary in profile.

5. An improved picture frame made of paper strips of different widths wound up successively in shape in which the wound up layers of paper strips are displaced in transverse direction in order to produce a profiled body, to increase the resisting capa-

bility of the body and to prevent the warping of the frame, the rear edge of said frame being irregular in profile corresponding to the front edge because of said displacement.

6. An improved picture frame made of strips of paper wound up in shape in which the wound up layers of paper strips are displaced in transverse direction in order to produce a profiled body, to increase the resisting capability of the body and to prevent the warping of the frame, the rear edge of said frame being irregular because of said displacement, a strip of stronger paper than the wound up strips attached to the body to form the ledge designed to receive the picture and beads upon said separate strip to form ornaments.

7. An improved picture frame made of paper strips of different widths wound up successively in shape in which the wound up layers of paper strips are displaced in transverse direction in order to produce a profiled body, to increase the resisting capability of the body and to prevent the warping of the frame; the rear edge of said frame likewise presenting an irregular profiled appearance because of said displacement, a stronger strip of paper than the wound up strip attached to the body to form the ledge designed to receive the picture and beads upon said separate strip to form ornaments.

In testimony whereof I affix my signature in presence of two witnesses.

WALTER OPEL.
